UNITED STATES PATENT OFFICE

WILLIAM A. BUCKNER, OF FRESNO, CALIFORNIA

SLOW MOTION ROTARY SPRINKLER

Application filed April 4, 1929. Serial No. 352,380.

This invention relates to sprinklers such as are arranged to be mounted in connection with underground water systems to water large areas, such as park lawns, golf courses and the like.

One of the major objects of the present invention is to provide a sprinkler of the opposed-nozzle reaction-rotation type, with a means so that the water passing through the 10 sprinkler head and before reaching the nozzles, will positively rotate the head independently of the rotary motion imparted thereto by reason of said opposed nozzles. By 15 means of this arrangement the separate rotation imparting means may be coordinated so as to act in conjunction with or against each other, as may be deemed best. This allows a great range of speeds of the head to be obtained without changing the velocity of flow 20 of the water, and enabling a certain desired speed to be maintained regardless of the velocity.

A further object is to provide a sprinkler of the telescopic or disappearing type (that 25 is one which drops of itself so that it is flush with the ground when the water is turned off) having this positive rotation structure arranged in connection therewith so that the 30 sprinkler head will be positively rotated as soon as and only when it lifts to its proper 35 operating position under the influence of the water pressure. This feature permits a sprinkler of this type of much greater range of operations to be permanently mounted in connection with underground piping, than is the case with the ordinary disappearing type of sprinkler head, and without the use of an unduly large sprinkler or a great water pressure.

40 A further object of the invention is to produce a simple and inexpensive device and yet one which will be exceedingly effective for the purpose for which it is designed.

These objects I accomplish by means of 45 such structure and relative arrangement of parts as will fully appear by a perusal of the following specification and claims.

In the drawings similar characters of reference indicate corresponding parts in the 50 several views:

Fig. 1 is a sectional elevation of my improved telescopic sprinkler shown in its retracted or non-operative position.

Fig. 2 is a similar view showing the sprinkler head raised to its operating position.

Fig. 3 is an enlarged cross section on the line 3—3 of Fig. 2.

Referring now more particularly to the characters of reference on the drawings, and particularly at present to Figs. 1 to 3 the 60 sprinkler comprises a base member 1 adapted to be screwed onto an upstanding underground pipe. Removably secured to said member is an upstanding and relatively large cylindrical casing 2 which projects up to the 65 ground level as shown. Secured in and projecting upwardly from the top of the member 1 is a relatively small pipe 3 which is surrounded by an enlarged head or cap 4 having tangentially disposed and oppositely facing lateral passages 5 therethrough leading 70 to the sides of said head from the top of the pipe.

Slidable and turnable on the pipe 3 (which also forms a stationary spindle) is the body 75 of the sprinkler head, which is a cylindrical member 6, only the base portion 6a of which has sliding engagement with the pipe; the remainder of the body being of considerably greater diameter than the pipe and of slightly greater diameter than the cap 4.

Fitted on top of the body is a hollow cap 7 provided with rotatably adjustable nozzle-nipples 8. These nipples are arranged in opposed and upwardly sloping relation to each other and have radial slits 9 in the sides to control the reaction rotation of the sprinkler head. This cap above the nozzles is provided with an enlarged overhang or hood 10 which has a snug fit with the top of the 100 casing 2 when the sprinkler body is in its lowered position, as shown in Fig. 1. This hood of course protects the nozzles from contact with any objects above and also prevents the casing from being possibly filled up with 105 dirt and other débris. The bottom of the body then rests on top of the member 1, while the cap 5 is then inside the cap 7.

The pressure of the water passing through the pipe 3 and into the chamber formed in 110

the sprinkler body through the passages 5 immediately causes the body to rise in the casing, due to the restricted size of the nozzles 8 which causes a back pressure to be set up in the body. As soon as the body is fully raised the top of the lower reduced portion 6a bears against a gasket 11 under the cap 4, maintaining a water-tight seal between these parts. The cap 4 is then horizontally alined with a plurality of inwardly projecting vertically alined ribs or vanes 12 formed in the body. The water issuing tangentially from the passages 5 of the member 4 impinges against these ribs and sets up a positive rotation of the sprinkler body, as will be evident. This rotation only takes place when the sprinkler body is fully raised, since only when the body is in such position are the vanes alined with the passages 5. 10 The nozzles 8 being adjustable the slits 9 therein may be readily positioned so as to partially neutralize this positive rotation of the body or they may be turned so that the reactionary rotation due to these slits will 15 act in conjunction with the positive rotation of the body, as may be desired according to the water pressure available and other conditions.

From the foregoing description it will be 20 readily seen that I have produced such a device as substantially fulfills the objects of the invention as set forth herein.

While this specification sets forth in detail the present and preferred construction 25 of the device, still in practice such deviations from such detail may be resorted to as do not form a departure from the spirit of the invention, as defined by the appended claims.

Having thus described my invention what 30 I claim as new and useful and desire to secure by Letters Patent is:

1. A rotary sprinkler comprising a vertical water passage spindle, a sprinkler head turnably and slidably mounted thereon and 35 enclosing the upper portion of the spindle, a discharge outlet from the head of restricted area relative to the spindle passage whereby water entering the head from the spindle will cause the head to be lifted, and 40 means between the spindle and head for causing the latter to be rotated by the flow of water into the head only when the latter is in its raised position.

2. A rotary sprinkler comprising a vertical water passage spindle, a sprinkler head turnably mounted thereon, said head including a body enclosing the upper portion of the spindle and formed at its lower end to 45 slidably engage the spindle but being of enlarged bore above the spindle engaging portion, an enlarged cap on top of the spindle having opposed tangentially arranged side 50 passages communicating with the interior of the spindle, discharge outlets from the head 55 toward its upper end of restricted area rela-

tive to the cap-passages, and vertical vanes projecting inwardly from the head just above the lower spindle-engaging portion thereof and arranged to have a running fit with the ends of the cap and to lie in the horizontal plane of the cap passages when the head is raised to its full extent on the spindle.

In testimony whereof I affix my signature.

WILLIAM A. BUCKNER.
